DESIGN FOR A FRUIT JUICE EXTRACTOR

Thomas L. Hand, Cincinnati, Ohio, assignor to Foster L. Talge, Kansas City, Mo., doing business under the name and style of Rival Manufacturing Company

Application April 30, 1937, Serial No. 69,069

Term of patent 14 years

To all whom it may concern:

Be it known that I, Thomas L. Hand, a citizen of the United States, residing at Cincinnati, in the county of Hamilton and State of Ohio, have invented a new, original, and ornamental Design for a Fruit Juice Extractor, of which the following is a specification, reference being had to the accompanying drawing, forming part thereof, in which

Figure 1 is a perspective view of a fruit juice
extractor showing my new design.

Figure 2 is a side elevation of the fruit juice

I claim:

The ornamental design for a fruit juice ex-tractor, substantially as shown.

THOMAS L. HAND.
